BALANCED COMPRESSOR

Myron F. Hill and Francis A. Hill, 2nd,
Westport, Conn.

Application September 1, 1938, Serial No. 227,954

10 Claims. (Cl. 230—141)

Our invention relates to drive devices for toothed gears, one within and eccentric to the other, operating as a displacement mechanism for pressure fluids, particularly for the compression and expansion of gases, and fluid balance systems tending to float the rotating members off from their bearings so that they may operate under pressures greater than the bearing surfaces themselves can carry. Many of its features are useful in connection with liquids.

In the patent to Myron F. Hill No. 1,682,564 a displacement rotor or gear mechanism was shown for such purpose in which the outer rotor was driven by a motor shaft acting as a drive device in order to maintain the tooth contacts tight, regardless of backlash whether intentional or due to wear. These tooth contacts separated chambers between the teeth while they were closing in a compressor (or opening in an engine), and the efficiency of the mechanism largely depended on keeping the contacts tight, since openings between the teeth permit pressure gases in a chamber to escape to lower pressure chambers without accomplishing intended results.

One way of maintaining such contacts tight is to connect the drive device to the outer rotor, and the patent above mentioned employed a driving plate or "bell" which was mounted on a motor shaft and carried an outer rotor near its outer perimeter. These parts rotated in a casing. When used for compressing air to higher pressures, to 100 lbs. for example, the pressure seeped out through the running joints into the casing and to the back of the driving plate, forcing the rotors against the front cover plate, causing friction, heat, and loss of power; and, with the lubricant finally adopted for substantially isothermal air compression, causing it to gum and retard operation. Various efforts were made to overcome these obstacles, such as pressure balancing areas, thrust bearings, etc., but in that mechanism they proved too difficult and uncertain to be relied upon. Journal bearings were also inadequate for the heavy work the rotors were capable of performing, due to the necessity of tight bearing fits for centering the rotors, and the inevitable heating and "freezing" that ensued.

Our invention aims to solve these problems and provide means to enable the rotors to successfully perform the high pressure work of a piston and cylinder displacement mechanism now generally used for these purposes.

In the patent to Myron F. Hill, 1,682,565, the rotors were mounted between two side walls

which are secured to each other, so that they received equal gas pressures from the rotor chambers between them, containing gas pressures varying from chamber to chamber.

5 The driving bell on the drive shaft extended over one wall, and centered and drove the outer rotor. Both shaft bearings were on one side of the rotors so that any lost motion inherent sooner or later in all useful bearings, caused the 10 axis of the shaft to run at an angle to the axis of the rotors provided by the side walls. So that another feature of our invention is applying a drive device mechanically balanced on bearing members with relation to the rotor that it drives, 15 to prevent the rotor from being tipped by the drive device out of its true plane of action. The construction in the above mentioned patent did not accomplish this result since the bearings on one side of the shaft would be loose so that their axis would not be normal to the plane of action provided for the rotors. This caused the drive rotor to cant, which resulted in point contacts between the teeth of the two rotors instead of the necessary line contacts across the teeth from 20 one side wall to the other, allowing escape of pressure gases between the teeth at either side of the point of contact. The effect of such crevices in liquid pumps is of minor import, but in compressors, particularly at high pressure they destroy efficiency.

25 One way (but not the only way) of getting and maintaining proper tooth action is to drive the outer rotor by a cylinder acting as a pulley or as an armature shaft, or by some other suitable device mounted on bearings on each side of the center line of the rotors, preferably outside of the tooth chamber side walls. Both the drive rotor and the driven rotor will then rotate in the same plane. Another method of securing this 30 result appears later.

35 In order to float rotors off from their bearings, liquid pressure is supplied from the higher pressure port or passageway, the liquid being conducted to recesses or channels which may be located between a plurality of landings or ruffles which constitute the bearings proper, and on that side of the shaft or axial support sustaining the major radial thrust or load resulting from the fluid pressure in the rotor chambers. Recesses or 40 channels on the opposite side of the axial support may be connected to low pressure passageways or ports to prevent the accumulation of pressure which would counteract the balance. By this system of fluid balances the loads upon the bearings themselves is greatly reduced.

Another feature of our invention is a displacement mechanism capable of running efficiently at either low or high speeds, according to the power and speed applied, without manufacturing different sizes, and adapted to do the work of small or large units. This is accomplished by the above mentioned cylinder or other drive device capable of any speed or load. When the cylinder is in an armature, it eliminates the usual motor shaft.

Another feature of our invention is the stationary mounting of the outer fluid displacement member or gear inside of a stator field which is mounted inside a hermetically sealed casing, the armature preferably being divided in two, one half on each port plate, to balance electrical end thrust. Each side wall or port plate is secured to the other through the shaft which is mounted on bearings outside of the port plates. The pinion or inner rotor is caused to revolve around inside the outer fluid displacement member or gear. In this way both an electrical balance and a compression balance are provided. While this mechanism is described primarily as a compressor it is obvious that it may be reversed with respect to the ports and act as a motor; and when an electric device is incorporated it becomes a generator.

The types of rotors or gears described and claimed in the patent to Myron F. Hill, No. 2,031,888, or No. 2,091,317 may be used in our invention.

In the drawings:

Fig. I indicates a displacement mechanism with a motor belt drive, and mounted on a horizontally disposed reservoir.

Fig. II is a longitudinal section of such a compressor on line II—II Fig. I.

Fig. III is a section, on line III—III of Fig. II showing an end bracket with fluid passageways, 40 reduced in size.

Fig. IV is an inside view of one of the port plates on line IV—IV, Fig. II.

Fig. V is a section on line V—V, Fig. II, showing an end view of the rotors or gears.

Fig. VI is a section on line VI—VI of Fig. II showing passageway details of a port plate.

Fig. VII is a sectional elevation of another form of our compressor inside an electric motor, with the outer gear member stationary, with a split armature and with the inner rotor revolving on two centers around inside the outer rotor or gear member.

Fig. VIII, the right half shows the outer gear member of the form of Fig. VII fixedly mounted in a stator. The left half of the figure shows the half armature of the form of Fig. VII mounted on one of the port plates.

Figs. IX and X show port plate details of the form of Fig. VII.

Figs. XI, XII, XIII, XIIIa, and XIV show passageway and bearing details of the form of Fig. VII.

Fig. XV is a sectional elevation of Fig. XVI on line XV—XV.

Fig. XVI is a side elevation of one form of our invention shown in Fig. XV with the right hand cover plate, port flotation, and bearing members removed and the rotatable casing, and the housing in section in the middle.

Figs. XVII and XVIII show additional port plate details of the form of Fig. XV.

Fig. XIX is a detail of the pinion rotor bearing of the form of Fig. XV.

Fig. XX shows a magnified view of the "rifles" used in our bearings of the form of Fig. XV.

Figs. XXI, XXII, XXIII show other bearing details of the form of Fig. XV.

Fig. XXIV shows a motor (with the compressor inside) mounted on an air storage tank.

Fig. XXV shows a section on line XXV of Fig. XXIV.

Fig. I shows a compressor in a shell 1, driven by a belt 2, and a pulley 3 on the shaft of a motor 4. The compressor and motor may be mounted 10 on a storage tank 5. Figure I shows a left hand view of the compressor shown in sectional elevation in Fig. II.

Fig. II shows the compressor shell or casing 1, driven by the belt 2. Inside the shell (and driven by it) is secured the outer rotor 6, which drives the pinion rotor 7. The rotors 6 and 7 run between fixed sidewall or port members 8 and 9. The compressor shell 1 is carried by bearing members 10 and 11 journalled at 12 and 13, which 15 also carry the working load of the outer rotor 6. The pinion rotor is journalled on an eccentric bushing 14, which has sufficient axial length to provide suitable running clearances for the rotors 6 and 7. The stationary port members 8 and 9, eccentric bushing 14, end bracket 16, and collar 18 are fixedly mounted on the shaft 15 which may be a stationary bolt. The left end bracket 16 contains the low pressure passageway 17 and the high pressure passageway 18. At the right end of the shaft 15 is the stationary member 19. The end member 16 may be carried by a bracket 20 and secured thereto by bolts 21. When the nut 22 on the shaft 15 is tightened solidly it

fastens all the stationary parts 16, 9, 14, 8 and 19 30 rigidly together by thrusting them towards the bolt head 23. Member 6 has a running fit between port members 8 and 9. Bearing members 10 and 11 have enough looser side wall running fits as to avoid contact with both members 8 and 18, and 9 and 16 respectively. This shaft may 35 also have additional support at its other end as indicated by the bracket 24. The stationary shaft 15 and the member 19 may be one piece if desired.

In operation the shell 1 is turned by the belt 2, which causes the rotors 6 and 7 to rotate. Air or gas is sucked in through the passageways 17, 25 and into the intake port 26 (Figs. II, III, IV) and the opening rotor chambers 27 and 28 (Fig. V). The gas is then compressed as the 40 chambers reach the positions 29 and 30 and finally expelled out thru the discharge port at 31, high pressure passageways 32, and 18. This port has a length sufficient at 31a to overlap a rotor 45 chamber in which the pressure has been raised to the desired degree. It should be separated from the intake port 26, (Fig. V) by a travelling tooth contact between the rotors or gears across full mesh, and ends at about a point the length of a 50 chamber from where the contacts between the teeth begin to open, allowance for rotational speed being desirable.

From 18, the compressed gas or air may go to a storage tank 5 (Fig. I) thru the pipe 33. The 55 compressed gas may be drawn off from the tank thru a pipe and valve 34.

A pool of liquid used for cooling gas (air for example) during compression, for pressure balancing and for lubricating bearings is provided 60 in the tank 5 (Fig. I).

We prefer to circulate liquid through the running parts of our compressor by using the pressure of the compressed gas or air to send the liquid first to the three pressure balancing zones 65 and bearings at 12, 13 and 35. For this purpose

we put enough liquid in the tank 5 to always more than cover the lower end of the return pipe 36 (Fig. I), the upper end of which may be screwed or sweated into the shaft 15 at 37 (Fig. II). The air pressure above the surface of the lubricant in the tank sends the oil into the passageway 38 and into the bore of the shaft 15. In Fig. V the duct 40 connects bore 38 with the circumferential groove 41 to lubricate the eccentric bearing at 35 for the inner gear 1. This forced feed liquid is also introduced into the flotation channels between the rifles of the pinion bearing under the rotor chambers compressing gas and resists the resulting thrust of the pinion against the shaft on the compression side. The angular length of the groove 41 determines the flotation area of the zone to balance the radial thrust of the mean effective pressure in compression chambers 29, 30 and 30a.

In order to prevent this pressure from creeping around the shaft so far as to offset this "hydrostatic balance," the intake port may be extended inward as indicated at 42 in Figs. IV and V to uncover the ends of the recesses between the "rifles" on the inner bore of the pinion rotor and assisted by the angular groove 41a, release any pressure in them. These recesses and zones are discussed more at length below.

Figures IV and VI show how the oil is conducted through the passageway 43 to the grooves 44 (also Fig. II) in the port members 8 and 9. Because compression in the closing chambers tends to thrust the outer rotor away from the shaft, the load on bearings 12 and 13 has to be balanced by liquid pressure channels on the axial support on the sleeves or hubs of the side walls diametrically opposite the discharge port and compression chambers. Holes 45 and 46 providing a vent to the intake passage 25 at each end of the grooves 44, serve to prevent the high pressure liquid from extending too far around the axial support and upsetting the hydrostatic balance.

The liquid acting now as a lubricant leaks from the recesses or channels of the high pressure zone toward the low pressure zones between the running surfaces and into the intake port 26 and the balancing dummy intake port 47 in the port member 8. Any liquid leaking outwards from the pressure channels between the rifles of bearings 12 and 13 is diverted by the stuffing boxes or seals 48 and 49 into the cylindrical grooves 50 and 51 from whence it is sucked back through passageways 52 and 53 to the intake passageways 25 and 54 (where inrushing air shreds it into a sort of rain) and ports 26 and 47 and into the opening rotor chambers where it now acts as a coolant to suppress the rise of temperature which would result from adiabatic compression.

It will thus be seen, that a mixture of coolant liquid, lubricant and compressed gas passes through the rotors and is discharged out at the discharge port 31, through passageways 32, 18, and pipe 33 and into the tank 5, where the coolant finds its way to the bottom to repeat its circuit. Thus in this circuit the liquid has acted as a pressure balancing agent in the pressure zones, as a lubricant for the bearing rifles and areas around the pressure zones, and as a coolant for isothermal (so called) compression.

Obviously the amount of liquid flowing depends on the clearance in the journal bearings and the leakage from them which, assisted by the pressure created in the rotor chambers, determines

the extent of cooling. The gas or air may be drawn off at 34 as above mentioned.

A regulating valve for the lubricant may be inserted in the pipe 36 at 36a (shown diagrammatically in Fig. I) and may be hand regulated or automatic as elsewhere described.

Figure VII shows our compressor inside an electric motor, having casing members 55 and 56 with the outer gear 57 held stationary inside an electric motor stator 58. The right half of Fig. VIII shows the stator 58 with poles 59 arranged axially instead of radially as is common for most commercial motors. The coils 60 are wound around the field poles and connected in the usual way. The stator is preferably mounted inside a non-magnetic but rigid housing composed of two thin diaphragm members 61 and 62, hermetically enclosing them. This stator may be composed of a suitable number of poles. In Figure VIII we have shown the stator with 12 poles. The hermetically sealed housing members 61 and 62 prevent injury to the windings from refrigeration gases either during operation or when being repaired. The outer edges of the members 61 and 62 are clamped in the casing joint by means of bolts 55a, and the inner edges may be welded at 57a to the outer gear 57. The armatures comprise copper frames 63, 64 with laminations of magnetic iron 63a and 64a in the holes 63b and 64b, Fig. VIII. These poles vary in number as compared to the field poles in the manner well known to the electrical motor art.

The armature is composed of a sufficient amount of magnetic material to cooperate with the stator efficiently. In order to avoid electric end thrust we show the armature composed of two members 63 and 64, mounted on and keyed to port plates 65 and 66. These port plates are keyed to the shaft 67. On the shaft and keyed to it is an eccentric bushing 68 on which the pinion gear 70 is free to rotate. This bushing 68 is sufficiently thicker than the gears 57 and 70 to provide the slight clearances between them and the side port members 65 and 66 for an efficient free running compressor.

When the nut 71 is tightened, the rotating parts 65, 66, and 68 are thrust against the shoulder 72 and rigidly fixed in position.

The armatures 63 and 64 drive the port plates 65 and 66, the shaft 67 and the eccentric bushing 68 which causes the pinion gear 70 to be rolled around inside of the outer gear 57. So that in effect the outer gear 57 causes the inner gear 70 to rotate on its own center while being carried around the shaft center by the eccentric 68 thus providing relative rotation between the rotors.

The left half of Figure VIII shows the armature 64 mounted on the port plate 66 and shaft 67.

This eccentric throw of the pinion 70 creates a dynamic unbalance which we prefer to restore by cutting out sufficient metal for the purpose in the port plates as indicated at 74 and 75 (Figs. VII, VIII, and X).

The axial supporting shaft 67 has outboard end bushings 76 and 77 which may have end closure and bearing members 78 and 79. The shaft has three interior passageways 80, 81, and 82. Passageways 81 and 82 are connected together as shown in dotted line in Figure VII.

In operation, gas is sucked in through the passageway 83 in the casing member 85, the cylindrical groove 84, the intake port 85 (Figs. VII, IX and X) and into the opening rotor cham-

bers. The other port plate 66 may or may not have dummy or operating ports. In this case we have shown a dummy intake port 86 opposite to an operating intake port 85. Two discharge ports 87 and 88 in port plates 66 and 65 cooperate in discharging gases from the compressor. Having been compressed the gases and entrained coolant liquid in them are discharged through ports 87 and 88, into passageways 89 and 90 and into the shaft passageway 80 thence out into the oil and gas separating chamber 91 issuing through the hole 92 which is of course rotating with the shaft at motor speed. Separation of the lubricant from the gas may be assisted by the cupped baffle plate 94 and disc 93. The passageways 80 and 81 may be plugged at 96 and 97 as indicated in Fig. VII. The baffle plate 94 may have holes near the shaft at 95 if desired. While we have shown only two such baffle plates it is obvious that any number may be added so as to get efficient centrifugal liquid from gas separation. The clean gas then emerges from the compressor casing at 98 ready for use—either to blow up tires, or for a refrigeration cycle.

After separation the pressure in chamber 91 forces the liquid through the passageway 99 and into the cylindrical groove 100 (Figs. VII and XIV) around the shaft, through the hole 101 and into the shaft passageways 81 and 82. The bushings 76, 77, and the recesses in the eccentric bushing 69 receive pressure balancing liquid from the passageways 81 and 82 by way of ducts 102, 103 and 104 respectively, (Figs. VII, XI, and XIII). Ducts 102, 103 and 104 empty into the grooves 102a, 103a and 104a (Fig. XI) feeding channels 102b, 103b and 104c between the rifles of the various bushings. Each end of the shaft is subjected to the same discharge pressure so that there is no unbalanced axial thrust and the whole compressor is thus in substantial hydrostatic, mechanical and electrical balance.

The intake ports may have undercuts at 105 Fig. IX to uncover the ends of the channels 104c in the eccentric bushing bearings to prevent the force feed liquid pressure from creeping too far around the central shaft.

The outer bearings may be relieved from a similar unbalance of pressure by such grooves as 106 Fig. XIV and 107 Fig. VII which allow the liquid to escape from the channels into the low pressure areas around the nut 71 and the shoulder 72.

As the liquid seeps from the channels and from the spaces between the rotors or gears and their port plates it is flung out into the casing from whence it drains by gravity into the casing depressions 108 and 109, through the passageways 110 and 111 and 112 into the intake passage 83 from whence it may be sucked back into the compressor with the incoming gases.

If the chamber 91 is unable to store enough liquid for operation, it may be tapped off as indicated in dotted lines at 113 into some storage chamber (not shown) and then returned at full pressure and sprayed into the intake at 114 (dotted lines) and also returned at full pressure to the duct 99 for lubrication and flotation. Duct 99 in this instance would have no direct connection with duct 113.

In Figure XV is shown an outer housing 120 having ribs 121 within which is mounted a stator of an electric motor, having for example laminations 122, holding coils 123, 124 in circuits 123a and 124a (Fig. XVI) suitable for two or more phases of an alternating current, one of which in a small motor might be a "split" phase.

The coils 123 may be for the running current and 124 for the starting current. These coils may carry two phases of alternating current. Windings for a three phase current may be employed or for any other kind of electric current. The stator may be adapted to cooperate with a squirrel cage type of armature 125, such an armature having greater inherent strength than a wired armature.

10 This armature or motor rotor 125, preferably of laminations inserted in a copper frame, may be mounted upon a steel or iron ring 126. The outer rotor may be integral with the ring 126 or keyed to it at 127.

15 As the armature 125 rotates it carries with it the armature ring 126 and the outer rotor 128.

This triple unit may be mounted upon side bearing members, 129 and 130 which are provided with suitable radial eccentric flotation channels 20 and bearings at 131 and 132. Those here employed will be described more in detail later. The members 129 and 130 may be of cast iron and are preferably keyed to the armature ring 126 at 127a and 127b. The inner rotor 133 may be journaled upon a concentric bushing 134. The bearings 131 and 132 in members 129 and 130 may be centered upon the axis 135 (Fig. XVI) of the outer rotor while the holes fitted to the fixed shaft or bolt 136 are centered upon the axis 137 of the inner gear. The bushing 134 may be of bronze or hardened steel, or of any other suitable bearing material to cooperate with the rotor 133 that turns upon it, it being understood that the rotor 133 may be, and preferably is of hardened steel, its 30 bore being provided with channels 138 (see Fig. XVI) separated by rifles engaging the bushing similar to those shown in Fig. XX, riding upon liquid films between the rifles and bushing, described more in detail later.

25 The bushing 134 is longer axially than the rotors 128 and 133 to provide film spaces between the side walls and the rotors. Sometimes the bushing exceeds the rotors axially by from one ten thousandth to one and a half thousandths of

30 35 bore being provided with channels 138 (see Fig. XVI) separated by rifles engaging the bushing similar to those shown in Fig. XX, riding upon liquid films between the rifles and bushing, described more in detail later.

40 The bushing 134 is longer axially than the rotors 128 and 133 to provide film spaces between the side walls and the rotors. Sometimes the bushing exceeds the rotors axially by from one ten thousandth to one and a half thousandths of 45 an inch according to conditions of use; and when the side or port members 139 and 140 are bolted solidly against its ends, by the bolt 136, their inner walls leave the rotors free to rotate.

The port members 139 and 140 may be of any 50 suitable material, preferably magnetic, so long as their inner walls cooperate in running qualities with the two gears.

The bushing 134 and port members 139 and 140 are held in correct relative location by the pins 55 141. The bushing is centered on the bolt 136 which in turn is tightly fitted to the side port members 139 and 140 and to the cover members 142, and 143. The bolt is keyed at 144 to the latter to prevent its rotation.

60 By this arrangement all lathe work is concentric except the bores of the members 139 and 140 which alone have accurate eccentricity (with respect to the bearings 131, 132) equal to that of the rotors.

65 The outer edges of the covers 142, 143 may be bolted, riveted or welded to the casing 120 in any well known manner, in accordance with usual practice.

The bolt 136 not only centers the bushing 134 but binds it, the two port members 139, 140 and the covers 142, 143, tightly together.

The armature 125, Fig. XVI, shown in the drawings may have twenty-nine squirrel cage inductive copper bars 145 (Fig. XV) set up mechanically 75 and electrically in plural phase motors, perhaps

of the split phase capacitor supplied type, which have no switch members within the motor. While this may be one form, it is well within the spirit of this invention to substitute any other type of motor having either electrical, or fluid pressure or mechanical drive.

The stator 122 may have twenty-four spaces 146 for field coil mounting, preferably with duplex field windings as at 123 and 124, one for starting and running, the other for running mainly, all wired as indicated in broken lines. The coils 124 may carry the split phase and the coils 123 may carry the main current from one wire of a three wire system. This arrangement provides 1800 R. P. M. Any other speed may be provided including a return wire. Three wires for this equipment from the capacitor enter the casing through gas and pressure tight insulated entrances, indicated at 148. These wires are connected to the coils in the usual manner for such 20 motors.

As the armature 125 drives the outer rotor or gear, that gear drives the inner rotor or gear 133 which rotates upon its journal on the bushing 134 opening and closing tooth spaces between the 25 teeth. Since the outer gear drives the inner gear the teeth make the fluid tight engagement where the chambers are closing, an arrangement providing also a longer suction entrance 149 (Fig. XVII) to the chambers that are opening than when the 30 inner rotor drives the outer rotor.

Our continuous contact contours for holding graduated pressure in successive chambers between the suction port 149 and the discharge port 150 provide high pressure ranges.

The discharge port may begin at 151 (Fig. XVIII) for low gas pressure and at any point, such as 152 for higher gas pressure. 152 should be located to connect with closing rotor chambers at the point where the desired discharged pressure 40 is attained in these chambers.

The port ends at full mesh are separated preferably by a tooth driving engagement at a little less than the angular length of a tooth and tooth space. The arrow 153 in Fig. XVI indicates this 45 distance and location when the above mentioned rotors are employed, the engagement occurring partly upon the opening side of a line through the axes 135 and 137 of the rotors (Fig. XVI).

With such rotors, the teeth maintain tight engagement regardless of wear from the end 154 of a crescent area to the end of the driving range near the point 155.

The suction port may extend from the point 55 155 to 154 though to shorten it at either or both ends does little if any harm to its cooperation with the rotor chambers.

The open space between the teeth at open mesh extends from about 156 to 154, these points being determined as a rule by the intersections of two 60 circles, one touching the inner tips of the outer rotor teeth and the other touching the outer tips of the inner rotor teeth.

Our rotors or gears are designed as follows:

Suitable circular arcs for the convex outer tooth faces are first decided on, and an inner mating tooth generated by it using a Fellow's gear shaper if desired for generation purposes. The backing off gear of the Fellows machine is unhooked, and a clapper form of tool is arranged on the ram, cutting on a down stroke and lifting off from the work on an up stroke. Four of the eight teeth of the inner rotor may be cut by this method, and after indexing either tool or blank one tooth division—45° for 8 teeth—the opera-

tion may be repeated to generate the other four teeth.

During generation, both blank and tool rotate upon the axes 135 and 137, one complete rotation of the tool generating one tooth space in the blank.

The outer rotor merely has repetitions of the selected arcs making up the tooth form. The centers of the arcs of the teeth and of the tool have to be well outside of the outer pitch or ratio circle, at a distance determined most easily by experiment. The proportions shown in Fig. XVI are about right. If the centers of the arcs are too near the ratio circle, the tool will undercut the portions of teeth engaging from 158 to 155 ruining the rotors. A slight amount of back lash, perhaps a couple thousandths of an inch, so that teeth may not wedge at full mesh, in case of uneven expansion due to heat, is desirable. This may be accomplished best by regenerating the inner rotor, after indexing it a degree or two. The bottoms of the tooth spaces of the outer rotor gear should clear the tops of the inner teeth in every position across full mesh a thousandth or two of an inch.

In M. F. Hill Patent No. 2,031,888 are shown and illustrated the latest form of rotors having a difference of one tooth. In those rotors a full open rotor chamber has a total depth of four times the eccentricity, and 6 by 7 teeth were about as few as may be used for substantial pressure with efficient and durable drives. In the rotors shown in this case the curves have identical contours in principle but based on a 4 to 5 ratio. Since they have 8 by 10 teeth they have greater durability and driving efficiency than the 6 by 7 rotor and yet being based upon a 4 by 5 ratio in a given diameter have a greater depth of chambers due to the greater eccentricity.

A fair comparison of these new rotors would be with 8 by 9 rotors involving the principle set forth in Patent 2,031,888. Those 8 by 9 rotors would have an eccentricity of slightly over half that of corresponding 4 by 5 rotors and when the relation of the total rotor diameter is taken into account the volumetric capacity of these 8 by 10 rotors is not far from twice that of the 8 by 9. It will be noticed further that any one tooth of the outer rotor engages but four alternate teeth of the pinion, the other intervening four teeth being successively engaged by an adjacent tooth of the outer rotor. In fact five alternate outer rotor teeth engage four alternate pinion teeth and the other four of the pinion are engaged by the remaining five teeth on the outer rotor. In other words this may be a duplex system of rotors approximately doubling the capacity of an 8 to 9 pump with equal driving efficiency. The driving relation is much the same as in two sets of 4 to 5 rotors with staggered teeth. Such a staggered system might be used with a partition between the rotors, and ports in the partition to both rotors, and port plates on the outer sides of the rotors.

These improvements depend upon a difference of two teeth as distinguished from a difference of one.

If a difference of three is desired the relative capacity is less and the ratios are multiples of three.

Attention is called to the fact that the doubling of the numbers of the 4 by 5 ratio has not interfered with the original driving relation between them, since it is only the extreme inward portion of the circular formed tooth of the outer

rotor which has been cut into, to provide a tooth space; and the corresponding portion of the pinion tooth spaces is occupied with the inserted tooth. The lost radial displacement depth of the portions of the tooth and tooth space which have been so altered is but a slight fraction of their original total depth and height respectively because of the original flatness of the curves where altered. The widths of the teeth are preferably about as illustrated.

The inner rotor may have radial slots 159 as indicated filled with high pressure liquid—or oil from grooves 182, 183 (Figs. XVII, XVIII)—so that when used in air or gas compression leakage of high pressure gas across the ends of the teeth is checked. These slots 159 tend to leave films upon the side walls of port members 139 and 140 which act as films for the outer rotor teeth preventing leakage of gas over their ends. This film seeps over the ends of the outer rotor and into the space around the members 129 and 130 and inside the armature ring 126 from whence it assists in lubricating the journals 131 and 132 in the low pressure areas and then draining into the low pressure region within the casing members 142 and 143. The liquid drains downward to the bottom regions 160 and 161 in Figure XV which are interconnected by the groove 162.

In functioning, the gas to be compressed enters the casing at 163 and is sucked through the motor parts, cooling them, and is then sucked into the bottom passageway at 164 and up through the casing 143 and into the intake port at 149. Any liquid that may have gathered at 160 or 161 is sucked with the gas up into the intake port 149 thus preventing the liquid level from rising higher than the opening at 164 and so obstructing the rotation of the armature or soaking the stator coils.

The compressed gas and excess liquid is discharged through the discharge port 150 (Fig. XVII) into the passageway 165, through the check valve 166, and at 167 into the high pressure chamber 168. As indicated at 167 this high pressure gas enters this chamber 168 tangentially being choked so as to set up a swirling action. This swirling causes the liquid to be thrown out against the walls 169 where it drains into the bath 170, preferably in a cylinder standing on end, acting as a pressure storage container. If cooling is desired, the liquid is cooled as it drains down the side walls. The compressed gas may be drawn off at 171 above the liquid level and then pass through any usual refrigeration cycle of cooling coils and expansion chamber before returning to the intake at 163. The ball check 166 prevents compressed fluids from "blowing back" into the intake 149, through the rotors or causing them to rotate backward, when current is cut off.

While I show the chamber 168 as a part of the compressor housing it may also be a separate tank or drum with pipes replacing passageway 165 and passageway 171 mentioned above.

Due to the high pressure existing above the surface of the liquid bath 170 and the low pressure within the compressor casing, this liquid is forced upward for bearing lubrication and hydrostatic balancing as follows:

Having entered the passageway 172 the liquid is forced up to preferably a valve 173 electromagnetically controlled and diagrammatically illustrated by solenoid coil 174 which is in circuit with the motor and said valve is closed normally and is opened the moment current passes into the mo-

tor. Liquid then enters the hole 175 in the bolt 136 and by means of the holes 176 and 177 lubricates the bearings and fills the flotation recesses in the high pressure regions at 131 and 132 of parts 129 and 130 respectively. The holes 176 and 177 are diametrically opposite the discharge port 150. Thus liquid pressure to provide a counterthrust to the radial pressure on the inside of the outer rotor compressing chambers, and the balancing areas in these channels may be so proportioned by means of grooves 178 and 179 as to oppose or balance the radial thrust in the outer rotor. Two similar holes 180 and 181 force liquid into the above mentioned grooves 182, 183 and slots 159 of the pinion and also into that part of the pinion bearing under the compressing chambers of the pinion so that it too has a balanced radial thrust. For this purpose the grooves 182 and 183 (Figures XVII and XVIII) are widened at 184 and 185 respectively so as to introduce the pressure into the channels between the ruffles in this region. On the low pressure side of the pinion bearing the channels are connected to the intake passageway 164 by passageway 185a, Fig. XVIII, so that this pressure cannot creep around the shaft to upset this balancing function. Similarly channels in bearings 131 and 132 on the side opposite to that sustaining the major radial thrust may be open at their outer ends to the casing.

In Fig. XX is shown an enlarged view of the form of channels and ruffles I prefer. The bearing shaft is indicated at 186. The ruffles 187 are between the recesses or channels 188. The ruffles have two surfaces, 189 which may be tangential to the curve of the bearing shaft 186 and the arc portion 190 which has a circular curvature cooperating with the shaft surface 186. The bearing effect is similar to that of the "Kingsbury" thrust. If the rifle member travels in the direction of the arrow then the liquid supplied for compression first enters the space between the tangential portion of the rifle and is then swept onto the arc so that the rotating member tends to ride continuously upon a film of liquid without having metallic contact with its bearing. A plurality of ruffles provide as many bearing areas.

The friction load on the bearing under a given set of conditions is determined largely by the number and width of the recesses. The fit between them and the shaft should be responsive to the exigencies of the bearing. The material of which this bearing is made is a non-friable material and preferably tough and hard to resist damage when particles of foreign grit enter. In order to prevent excessive flow the parts 129 and 130 may have bearing shoulders or hubs 191 and 192 respectively which substantially reduce such flow into the low pressure regions to that required for the functions of bearing, balancing and gas cooling enumerated.

In Fig. XXIV is shown an air compressor system for compressing air and cooling the liquid which absorbs the heat of compression in the rotor chambers. The motor 200, operating a compressor indicated at 201, taking in air through a cleaner 202, is mounted at 201a upon a vertical cylindrical tank or storage reservoir 203. The compressor discharges air mixed with a mist, introduced at the intake, through the pipe 204 into the tank at 205 (Fig. XXV) choked so that the air and mist are caused to whirl around inside the tank, throwing the mist outwardly by centrifugal force against the inner wall of the tank, down which it drains into the pool at the bottom.

The wall absorbs the heat from the liquid and delivers it to the surrounding air. The liquid in the bottom of the tank, under pressure of the compressed air, is forced through the strainer 206 and up through the pipe 207 to the compressor, where it enters the rotor chambers in a comminuted form as mist and repeats its cooling function, and enters the channels in the bearings as described. An exit 209, having a valve at 208, provides for the use of the compressed air.

In Figs. XXI, XXII, and XXIII I show another form of my bearing.

In Fig. XXI is a shaft 210, a casing 211, a rifled combined pressure balancing and bearing bushing 213, having bearing rifles and pressure zones of channels with confining end ring members 212 and 214, undercut at 216 and 215 respectively. (Figs. XXII, XXIII.)

Pressure forces oil or other liquid into the passageway 217, and undercut groove 216 (Figs. XXIII and XXI) extending across the ends of a series of rifles and into the channels (see 188 Fig. XX) between them. The rotation of the shaft then sweeps the liquid from the channels onto the bearing rifles or landings (see 186 Fig. XX) thus causing the shaft 210 to ride on a series of liquid surfaces on the rifles under hydrostatic pressure. The length of the arc shaped groove 216 determines the high pressure area, which is designed sufficiently large to meet load requirements.

In order to prevent hydraulic bearing area pressure from creeping so far around the shaft as to offset the load balancing pressures from the groove 216, another groove or undercut 215 with an escape passage 218 to low pressure is provided. The groove 215 extends over the end of a sufficient number of channels to satisfactorily unload the zone where needed.

While not absolutely necessary, I prefer that the lubricant be forced in at one end of the zone, thence into the high pressure channels, thence over rifles and to the low pressure channels, and then allowed to escape at the other end inside of the ring. The exit 218 is so located above the shaft that when the shaft is stationary, there is no tendency for lubricant to drain through it away from the zone. Close running bearing clearances at the ends of the channels, prevent the zone from becoming completely dry during periods of idleness.

What we claim is:

1. In a mechanism for operation on or by fluids, rotors or gears mounted eccentrically to each other, one within the other, said rotors having teeth forming chambers between them which open and close during relative rotation, said teeth having contours maintaining continuous contacts between said chambers while performing fluid pressure functions, a support for said rotors providing said eccentric mounting, said support including pressure confining side walls closing said chambers at their ends, high and low pressure ports connected alternately to said chambers for supplying and receiving fluid for said operation, bearings for said eccentrically mounted rotors disposed along said support to prevent said rotors from tilting at angles to each other, high pressure fluid areas between said support and rotors said areas located between said support and rotors, on both sides of a middle plane thru said rotors normal to their axis, and so proportioned as to substantially balance the radial mechanical pressures of said rotors upon said eccentric bearings, said high pressure areas

being connected by a duct to said high pressure port, and low pressure regions between said support and rotors, and opposite to said high pressure areas, having a duct connection to a low pressure region; whereby varying fluid pressures in said rotor chambers create opposing forces to corresponding mechanical pressures upon said bearings.

2. The combination claimed in claim 1, in which the low pressure duct connection acts as an escape connection for liquid leaking from the high pressure areas to the low pressure region, said escape connection leading to the low pressure port, whereby shaft seals or packing are rendered unnecessary.

3. In a mechanism for operation on or by air or gas, rotors or gears mounted eccentrically to each other, one within the other, said rotors having teeth forming chambers between them which open and close during relative rotation of said rotors, members providing ports to receive gas from and discharge gas into said chambers, said ports being so proportioned and located with respect to said chambers as to provide varying fluid pressures in said chambers during opening or closing thereof, said teeth having contours maintaining continuous contacts between said chambers, said chambers during opening or closing containing said varying fluid pressures and being kept in sealed relation by the driving contacts between said teeth to check air or gas leakage under pressure from one to another while performing pressure functions, a support for said rotors providing said eccentric mounting, said support including relatively fixed pressure confining side walls closing said chambers at their ends, said side walls having a fixed relation to said support, and means to supply mist to said rotor chambers as their pressures vary, to act as a coolant to check change of temperature during variations of gas pressure in said chambers, said chambers, tooth contacts and ports being so located and adjusted as to prevent liquid locking or choking between high and low pressure ports at full mesh.

4. The combination claimed in claim 3 having a rotary centrifuge on said support with a driving connection with one of said rotors, and gas passageways between said high pressure port and said centrifuge, whereby the mist in said gas is separated by centrifugal force.

5. The combination claimed in claim 3, said rotors having a difference of two in the numbers of their teeth thereby leaving a crescent space between the teeth at open mesh, said low pressure port connected to said crescent space to increase the ease of passage of low pressure gases thru the low pressure port.

6. In a mechanism for operation on or by gas and liquid, rotors or gears mounted eccentrically to each other, one within the other, said rotors having teeth forming chambers between them which open and close varying gas pressure between them, said teeth having contours maintaining continuous contacts between said chambers during opening or closing of said chambers to check air or gas leakage from a chamber containing higher pressure to a chamber containing lower pressure while performing pressure functions, said teeth having a difference in their numbers of teeth greater than one, a support for said rotors providing said eccentric mounting, said support carrying side walls for said rotors closing their chambers at the ends thereof, high and low pressure gas ports and passage-

ways connected alternately to said chambers and disposed angularly about said support so as to be separated by chambers varying in their pressure, bearing members for each of said rotors between said rotors and said support disposed axially of said rotors to maintain line contacts between said teeth from one side wall of said rotors to the other side wall of said rotors.

7. The combination in claim 6 having means to supply mist to said chambers to check variations of temperature as their volumes and pressures vary.

8. The combination claimed in claim 6 having pressure areas between said rotors and said support supplied with fluid or liquid pressure from said high pressure port, said areas located to relieve the radial mechanical pressure upon said bearings of the varying pressures in said chambers.

9. The combination in claim 3 having the side walls fixed with relation to the eccentricity of said bearings, with said ports in said side walls.

10. The combination claimed in claim 6 having high and low fluid pressure zones along said support and between it and said rotary members located to oppose the radial mechanical pressure resulting from varying gas pressures in said chambers upon said rotors, ducts connecting said high pressure zones to said high pressure port, and said low pressure zones to a low pressure region, whereby the load on said bearings is reduced increasing the total load capacity of said rotors for compression.
